UNITED STATES PATENT OFFICE

LLOYD W. MOULTON, OF SYRACUSE, NEW YORK

CENTRIFUGAL GANG-CASTING MACHINE

Application filed October 21, 1931. Serial No. 570,168.

This invention relates to a centrifugal gang-casting machine as distinguished from the single babbitt casting machine shown in my Patent No. 1,675,657, July 3rd, 1928, but embodying certain features of the patent relating more particularly to the clutch and brake mechanism for controlling the rotation of the individual work-holders.

The machine is adapted to be used more particularly for casting Babbitt metal bearings in the crankshaft openings of connecting rods or pitmans commonly used as connections between the crank shaft and pistons of internal combustion engines, piston pumps, and analogous apparatus.

The main object of the present machine is to expedite the casting operations and thereby to greatly increase the output for a given period of time.

One of the specific objects is to provide means whereby a multiplicity of work-holders may be sequentially presented to a given point without interruption and to discharge the molten metal into the work while the work-holders are passing that point.

Another object is to provide means for automatically controlling the flow of the molten metal into the work when successively presented at the receiving point so that the flow will occur only while the work-holders are passing the delivery nozzle of the melting pot.

Another object is to provide the machine with means for automatically regulating the operation and speed of rotation of the work-holder so that the latter will be held against rotation when brought to the loading and unloading position and will be rotated at a relatively high speed immediately following the delivery of the molten metal to the work to assure the proper formation and cooling of the casting in transit from the delivery nozzle of the melting pot to the unloading and reloading position.

Other objects and uses relating to specific parts of the machine will be brought out in the following description.

In the drawings:
50 Figure 1 is a top plan of a centrifugal

gang-casting machine embodying the various features of my invention.

Figures 2 and 3 are enlarged vertical sectional views taken respectively along the lines of 2-2 and 3-3, Figure 1.

Figures 4 and 5 are detail sectional views taken respectively along the lines of 4-4, and 5-5, Figure 3.

Figure 6 is a horizontal sectional view, partly broken away, taken in the plane of line 6-6, Figure 2.

Figure 7 is a detail vertical sectional view taken along the line 7-7, Figure 6.

Figures 8 and 9 are enlarged detail vertical sectional views taken respectively along the lines 8-8 and 9-9, Figure 2.

Figure 10 is an enlarged detail vertical sectional view taken in the plane of line 10-10, Figure 3.

Figure 11 is a detail vertical sectional view taken along the line 11-11, Figure 9.

Figure 12 is an enlarged detail vertical sectional view taken in the plane of line 12-12, Figure 6.

Figure 13 is a diagrammatic plan view of the circular path of rotation of the work-holders and the several operations which take place at different positions of travel of the work-holder.

Figure 14 is an enlarged detail vertical sectional view taken in the plane of line 14-14, Figure 6.

Figure 15 is an enlarged detail horizontal sectional view, partly broken away, taken in the plane of line 15-15, Figure 2.

Figures 16 and 17 are enlarged detail horizontal sectional views, partly broken away, taken respectively along the lines 16-16 and 17-17, Figure 2.

Figure 18 is an enlarged elevation, partly in section, of the mechanism shown in Figure 15 taken along the line 18-18, Figure 15.

Figures 19 and 20 are enlarged detail vertical sectional views taken respectively in the planes of lines 19-19 and 20-20, Figure 15.

The main supporting frame comprises a substantially circular horizontal base —1—, and a motor-supporting base —2— secured to one side of the circular base —1— and 103

upon which latter is mounted an upright bracket —3— carrying at its upper end a suitable furnace or melting pot —4— of any suitable construction in which the metal used to form the castings is melted by any well-known melting process, see Figures 1, 2, 3 and 14.

The base —1— is provided intermediate its lower and upper ends with a substantially horizontal wall or partition —5— having a central hub —6— in which is secured the lower end of an upright post —7— which extends upwardly above the level of the outlet of the melting pot —4— and is provided at its upper end with a canopy plate or hood —8—, shown more clearly in Figures 1 and 2.

A plate —9— is secured by bolts —10— to the lower end face of the post —7— to engage the lower end face of the hub —6— for holding the post against upward displacement, said plate —9— being secured to the hub by pins —11— to cooperate with the bolts —10— for holding the plate and post against rotation relatively to the base —1—, said post being also provided with an annular flange —12— resting upon the upper end face of the hub —6— to support the post against downward movement and thereby to assist in holding the post in an upright position, see Figures 2 and 14.

The melting pot —4— is provided with an outlet opening —18— to which is secured a valve case —14— having an inlet port —15— and an outlet port —16—, the inlet port serving to receive molten metal from the outlet —13— and is preferably inclined upwardly and inwardly to communicate with the valve chamber while the outlet —16— of the nozzle —14— extends inwardly and downwardly from the valve chamber to overhang the paths of travel of the several inlet sprues leading to a corresponding number of work-holders on a rotary carrier hereinafter described so that as each sprue is registered with the outlet —16— of the nozzle —14— the molten metal may be caused to enter the same, Figures 2 and 8.

The passage of the molten metal from the inlet —15— to the outlet —16— is controlled by a valve —17—, Figure 2, which in turn is adapted to be opened and closed intermittently as each of the work-holders is successively registered with the outlet —16—, the operation of the valve being automatic and timed with the speed of rotation of the carrier for the work-holders in a manner hereinafter more fully explained, see Figures 1, 2, 3 and 8.

Rotary carrier

The upper end of the base —1— is provided with a horizontal annular bearing face —18— upon which is rotatably mounted a carrier frame —19— adapted to rotate about the axis of the post —7— with its lower end resting upon the bearing face —18—, said

carrier frame being provided with an inner supplemental section —20— which is secured by bolts —21— to the frame —19— and has its upper end provided with a hub —22— journaled upon the adjacent portion of the post —7— to assist in holding the carrier frame co-axial with the post, as shown more clearly in Figures 2 and 14.

The annular bearing —18— is formed upon an inturned flange on the upper end of the base —1—, said flange having its inner edge circular to form a side thrust bearing which is engaged by the marginal edge of the carrier section —20— to assist in holding the carrier co-axial with the post —7— as shown more clearly in Figures 2 and 14.

The flange upon which the horizontal annular bearing —18— is formed is provided with a plurality of, in this instance, three oil pockets —23— arranged in uniformly spaced relation circumferentially about the axis of rotation of the carrier for receiving a corresponding number of oil distributing roller units —24— which engage the underside of the adjacent portion of the carrier —19— for distributing the oil from the pockets —23— to the bearing surface —18— as the carrier is rotated about its axis as shown more clearly in Figures 6 and 12.

Each roller unit comprises a plurality of, in this instance, three rollers journaled upon a supporting pin —25— which, in turn, is mounted upon a yoke —26— having a central pendant plunger —27— which is slidable vertically in a socket —28— extending downwardly from the oil pocket —23— and is spring-pressed upwardly by a coil spring —29— in the lower end of the socket —28— to yieldingly hold the rollers —24— in engagement with the underside of the adjacent portion of the carrier —19—, see Figure 12, the purpose being to lubricate the flat bearing surfaces between the base —1— and carrier and thus permit the carrier to be rotated with a minimum friction and power.

Carrier rotating means

A gear ring —30—, shown more clearly in Figures 2, 6 and 14, is bolted or otherwise secured to the underside of the carrier section —20— concentric with the axis of the port —7— to mesh with a pinion —31— which is secured to a relatively larger gear —32—, the latter being journaled upon a post —33— on the base —1— for relative rotation, as shown more clearly in Figures 6 and 7.

A sleeve —34— is journaled upon the post —7— for relative rotation thereon and is provided with a spur gear —35— from which rotary motion is transmitted to the gear —32— through the medium of a speed reducing gear train —36— as shown more clearly in Figures 2, 6 and 7, the object being to cause the rotation of the carrier —19— at a relatively low rate of speed.

The sleeve —35— is also provided with a bevel gear —37— meshing with a bevel pinion —38— which in turn is secured to one end of a horizontal driving shaft —39— having its other end connected to an electric motor —40— or equivalent power device, said motor being mounted upon its supporting frame or bracket —2— shown in Figure 2, see also Figures 6 and 14.

10 The inner end of the driving shaft —39— adjacent the pinion —38— is journaled in a sleeve —41— which in turn is supported upon the adjacent portion of the partition —5— of the base —1— as shown more clearly in Figures 2 and 14, said gear —37— being preferably made in the form of a ring secured by bolts —37'— to the lower end of the sleeve —34— as shown more clearly in Figure 14.

15 It is now clear that even though the driving shaft —39— may be driven by the motor at a high rate of speed, the speed reducing gear train —36— will cause the carrier —19— to be rotated at a relatively low speed for a purpose hereinafter more fully explained.

20 The several gears of the train —36— are journaled upon an upright stud —33'— on the partition —5— of the base —1— as shown more clearly in Figure 7, some distance to one side of the motor shaft —39— in the direction of rotation of the carrier as shown in Figure 6 so that the gear —32— may project some distance beyond the periphery of the gear ring —30—.

Carrier lubrication

25 As shown more clearly in Figure 7, the base —1— is provided near its periphery with an oil reservoir —42— directly under the outer portion of the gear —32— for receiving a pump —43— having its suction side communicating through a screen —44— with the interior of the reservoir and its pressure side provided with a conduit —45—, (Figures 6, 7 and 14) leading to the lower end of a central vertical passage —46— in the upright post —7— as shown more clearly in Figure 14.

30 This oil passage —46— extends upwardly to about the level of the hub —22— of the carrier section —20— and is provided with branch oil passages —47— leading to the hub bearing —22— and sleeve —34— for lubricating those parts as the carrier is rotated.

35 The pump —43— is provided with an upright shaft —48— carrying a pinion —49— which meshes with the adjacent portion of the gear —32— so that the rotation of said gear through its connections with the motor driven gear sleeve —34— will also operate the oil pump to force the oil into the upright passage —46— and the post —7— and thence to the bearing —22— and sleeve —34— respectively.

Rotary work-holders

A gear ring —50— is bolted or otherwise secured to the upper end of the sleeve —34— some distance above the spur gear —35— to rotate with said sleeve about the axis of the central upright post —7— as shown more clearly in Figures 2 and 14 and is adapted to mesh with a plurality of, in this instance, six similar pinions —51— which are mounted upon a corresponding number of horizontal shafts —52—, the latter being arranged in uniformly spaced relation circumferentially around the axis of and radially to the upright post —7— to extend outwardly therefrom.

75 These shafts —52— are journaled in suitable bearing sleeves —53— which in turn are secured to the rotary carrier section —20— as shown in Figures 2, and 14, each shaft having its outer end provided with a pulley —54— keyed or otherwise secured thereto to rotate therewith, see Figures 2 and 14.

80 Each of these pulleys —54— is connected by a belt —55— to a superposed pulley —56— which is journaled in axially spaced bearings —57— upon a shaft —58— for relative rotation upon said shaft, see Figures 2 and 3.

85 The carrier —19— preferably consists of a circular frame concentric with the axis of the post —7— and having its lower end rotatably mounted upon the annular bearing —18— of the frame —1— in a plane between the gears —37— and —50— and its upper end extended some distance above the horizontal plane of the shaft —52— and provided with a substantially horizontal deck ring or plate —59— bolted or otherwise secured to said carrier to rotate therewith around the post —7—.

90 Associated with each of the belts —55— is a belt tightener —t— similar to that shown in my patent referred to, see Figures 2 and 14.

100 Upon this deck ring —59— are mounted a plurality of, in this instance, six upright housings —60— corresponding to the number of radial shafts —58— which are journaled in suitable bearings —61— in their respective housings —60— at opposite ends of the bearings —57— for the pulley —56— as shown more clearly in Figures 2 and 3.

105 Each of these housings —60— is provided with a brake drum —62— concentric with the axis of the corresponding shaft —58— and secured to said housing by bolts —63— and pins —64— as shown in Figure 3, said brake drum being arranged in axially spaced relation to the corresponding pulley —56—.

110 A combined clutch and brake ring —65— is splined by means of a slot —66— and pin —67— upon each of the shafts —58— to rotate therewith and to slide axially thereon and is interposed between the hubs of the corresponding pulley —56— and the adjacent 115

brake drum —62— for alternate frictional engagement therewith as it is shifted in opposite directions.

For this latter purpose, the adjacent ends of the pulley —56— and brake drum —62— of each set are provided with inner conical bearing surfaces —56'— and —62'— while the adjacent ends of the combined clutch and brake member —65— are provided with conical peripheral surfaces —68— and —68'— adapted to be alternately brought into frictional engagement with their respective friction surfaces —56'— and —62'— as the clutch member is shifted in opposite directions in a manner hereinafter described, see Figure 3.

It is now evident that when the carrier —19— is being rotated in the manner previously described about the axis of the post —7—, rotary motion will be transmitted to all of the radial shafts —52— through the medium of the gear ring —50— and pinions —51— and that this rotary motion will be transmitted by means of the belts —55— to all of the pulleys —56— which are free to rotate upon their respective shafts —58— when the clutch members —65— are shifted axially out of engagement therewith and into engagement with the brake drums —62— at which time the shafts —58— will be held against rotation.

On the other hand, when the clutch members —65— are shifted axially out of engagement with the brake drums —62— and into engagement with their respective pulleys —56—, rotary motion will be transmitted through said clutch members to their respective shafts —58—.

The outer ends of the several shafts —58— are provided with hubs —69— keyed or otherwise secured thereto to rotate therewith for receiving and supporting a corresponding number of work-holders —70— which are secured to their respective hubs —69— by bolts —69'— or equivalent fastening means to cause the work-holders to rotate with their respective shafts, see Figure 3.

Each of these work-holders —70— comprises a relatively large circular face plate —71— having one or more outwardly projecting pins or studs —71'— eccentric to the axis of rotation of the face plate —71— for receiving and supporting a corresponding number of pieces of work —a— shown by dotted lines in Figure 3.

Each piece of work —a— consists, in this instance, of a connecting rod or pitman commonly used in internal combustion engines for connecting the crank shaft to one of the pistons and for that purpose is provided at its opposite ends with hollow bearings —b— and —b'— adapted to receive respectively a portion of the crank shaft and one of the cross pins of the piston.

A suitable fan or blower —e—, similar to that set forth in my patent previously re-

ferred to, is mounted upon each of the face plates —71— to rotate therewith for causing the circulation of air around the bearing —b— of the work —a— through openings —f— and —g— which communicate with the interior of the blower —e— which is enclosed in a suitable housing —i— on the inner end of the face plate —71— as shown in Figures 1, 2 and 3 to assist in cooling the casting in its travel through the cooling arc.

The crank shaft bearings —b— are usually provided with babbitt or equivalent sleeves for direct engagement with the crank shaft and the purpose of the present invention is to project limited quantities of the molten metal into each of the bearings —b— of the several pieces of work as they are successively aligned with the discharge nozzle —16— of the melting pot —4— during the rotation of the carrier and then to rapidly rotate the work-holder with the work thereon about the axis of the bearing containing the molten metal for causing the latter to assume a cylindrical form within the bearing by centrifugal force without interrupting the rotation of the carrier.

Each of the work-holders —70— is provided with a central work-engaging boss or hub —72— which is secured by bolts —72'— to the face plate —71— and hub —69— co-axial therewith and having its outer end face disposed in a plane at substantially right angles to said axis for receiving and engaging the adjacent end of the bearing —b— of the work —a— as shown by dotted lines in Figure 3, it being understood that the opening in the bearing —b— will be substantially co-axial with the axis of the work-holder and held in that position during the casting operation, see Figures 2 and 4.

That is, the distance between the axis of the hub —72— and stud —71'— corresponds to the distance between the axes of the bearings —b— and —b'— of the work —a—.

When the several work-holders are successively brought to a predetermined position, as for example, that designated by the arc "load and unload", Figure 13, the operator will place one of the pieces of work in operative position upon the registering work-holder with its eye or bearing —b'— engaged with the stud —71'— and its other bearing —b— engaging the outer end face of the member —72— co-axial therewith to be clamped against the end face of said member in a manner presently described, see Figure 3.

Each work-holding plate —71— is provided with a plurality of, in this instance, three axially extending openings —73— arranged in uniformly spaced relation about its axis and relatively thereto for receiving a corresponding number of guide sleeves —74— through which latter are passed a like number of guide bolts —75—.

Upon the inner ends of each set of bolts 75— is mounted a bearing plate 76— to rotate with the face plate 71— co-axial with the corresponding shaft 58—, the outer ends of each set of bolts 75— serving to receive and support a clamping plate 77— which is also rotatable with the face plate 71— about the axis of the corresponding shaft 58—, see Figures 2 and 3.

10 The bearing plate 76— is located at the inner end of the face plate 71— while the clamping plate 77— is located some distance from the outer end of the work-supporting member 72— as shown in Figure 3, to receive the adjacent portion of the work between them when the clamping plate is moved 15 to its extreme outer position as shown in full lines in Figure 3 against the action of coil springs 78— which surround the inner ends of the respective bolts 75— and are interposed between the plate 76— and enlarged portions of the sleeves 74—.

While the several work-holders are being moved by the carrier 19— about the axis of 20 the post 7— through the arc indicated by the words "load and unload" in Figure 13, the corresponding clutch member 65— will have been moved endwise into engagement with the brake drum 62— to temporarily 25 stop the rotation of the adjacent shaft 58— and its work-holder 71— to allow the removal of the work with the casting therein from the work-holder and also to permit another piece of work —a— to be inserted 30 in proper position on the work-holder for receiving the molten metal.

That is, during the period of unloading and loading of the work from and in the machine, the clutch member 65— will be forced into 35 engagement with the brake drum 62— to stop the rotation of the work-holder while at about the same time or during the same period of unloading and loading the clamping member 77—, will have been moved axially 40 and outwardly to its open position as shown by full lines in Figure 3, it being understood that the rotation of the carrier is rather slow and that the period of non-rotation of the workholders about their respective axes and 45 opening movement of the clamping member 77— will be sufficient to allow the operator to withdraw the finished articles from the machine and to replace another piece of work upon the same work-holder.

50 As soon as the piece of work is properly placed in the work-holder the clamping member 77— is released and forced to its clamping position against the work —a— by means of the coil springs 78— and immediately 55 upon the closing of the clamping member 77— upon the work the clutch member 65— will be shifted out of engagement with the brake drum 62— and into engagement 60 with its corresponding continuously rotat- 65 ing pulley 56— thereby causing the work-

holder with the work thereon to be rotated at a relatively high speed.

In order to accomplish the automatic shifting of each clutch member 65— into and out of engagement with the brake drum 70 62— and pulley 56— the inner end of each shaft 58— is provided with a central socket 79— for receiving axially movable plunger sections 80— and 80'— which are telescopically connected end to end by a connecting pin 81—, the section 80— being provided with a diametrical opening for receiving the spline pin 67— by which the clutch member 65— is connected to its shaft 58— for relative axial movement thereon, 80 see Figure 3.

It is now evident that when the plunger sections 80— and 80'— are moved endwise in reverse directions, similar motion will be transmitted to the key pin 67— and through said pin to the clutch member 65—, but it will be noted upon reference to Figure 3 that a slight lost motion is provided for between the adjacent ends of the sections 80— and 80'— to assure firm frictional engagement of the clutch member with the brake drum 62— and pulley 56— aided by a coil spring 82— which is interposed between the adjacent ends of the sections 80— and 80'— as shown more clearly in Figure 3 in which it will be noted that the openings in the section 80'— for receiving the pin 81— are slightly elongated to permit said lost motion.

100 A plurality of brackets 83— are secured by bolts 83'— or equivalent fastening means to the underside of the upper deck 59— of the rotary carrier 19— to extend upwardly therefrom at the outer ends of the corresponding work-holders 70— for receiving and supporting a corresponding number of upright spindles 84— carrying at their upper ends a like number of hopper shaped conduits 85— for conducting the molten metal from the nozzles 16— to the work, when aligned with the nozzle 16.

105 These spindles 84— are adjustable vertically in the upper ends of their respective brackets 83— for properly centering the outlet ends of the hoppers 85— with the openings in the work —a— into which the molten metal is to be cast, said spindles being held in their adjusted positions by set screws 84'—, Figure 3.

110 The lower ends of these conduits 85— are disposed in substantially horizontal planes co-axial with the axes of the rotary clamping members 72— and 77— and extend through relatively larger central openings 77'— in the adjacent clamping members 77— to allow said clamping members to rotate relatively to the adjacent ends of the conduits 85— without friction therewith and to enable the molten metal to be dis- 115 120 125 130

charged axially into the corresponding bearings *b* of the work *a*.

The outer upper ends of the conduits *85* are open and disposed in a horizontal plane just below that of the lower end of the nozzle *16*, said discharge nozzle *16* and upper open ends of the conduits *85* being disposed equal distances from the axes of rotation of the carrier *19* so that as the latter is rotated about its axes the upper ends of the conduits *85* will be successively registered with the lower ends of the discharge nozzles *16* for receiving molten metal therefrom and allowing said metal to flow by gravity into the bearing *b* of the work *a*.

In order that the molten metal may be discharged into the conduits *85* without interrupting the rotation of the carrier *19*, the upper ends of the conduits are elongated circumferentially as shown more clearly in Figures 1 and 8, the circumferential length of the mouth of each conduit being sufficient to receive a full charge of the molten metal during the period of travel of the conduit past the outlet nozzle *16*, see Figures 1, 2 and 8.

The valve case *14* is provided with an upwardly projecting extension *14'* in which the valve *17* is guided in its vertical movement for regulating the flow of the metal from the melting pot to the nozzle *16*, said valve being normally closed by its own weight or by any other self-closing means, but is adapted to be intermittently automatically opened as the several conduits *85* are brought into registration with the discharge nozzle *16* by the rotation of the carrier *19*.

For this latter purpose the valve *17* is pivotally connected at *86* to the intermediate portion of a lever *87* which has one end pivoted at *87'* to the extension *14'* of the valve case *14* and its other end provided with an opening *86'* for receiving an upright operating rod *88*, shown more clearly in Figures 2 and 8.

This rod *88* is guided in its vertical movement in lower and upper bearings *88'* and has its upper end movable freely through the opening *86'* in the adjacent end of the lever *87* which is free to move vertically and assists by its own weight in closing the valve *17*.

The portion of the rod *88* directly below the adjacent end of the lever *86* is threaded and engaged by a nut *89* which is adjustable vertically on the rod and is held in its adjusted position by a lock nut *89'*, Figure 8.

The lower end of the rod *88* rests by its own weight upon one end of a bell crank lever *90* which is pivoted at *90'* to the frame section *3* and its other end provided with a roller *91*. The down-

ward movement of the end of the lever engaged by the rod *88* is limited by an adjustable stop screw *92* which is engaged in a threaded lug *92'* on the frame section *3* as shown more clearly in Figure 8.

The weight of the rod *88* engaging the lever *90* yieldingly holds said lever in engagement with the stop screw *92* at which time the nut *89* will be in slightly spaced relation to the underside of the adjacent end of the valve operating lever *87* to allow the valve to completely close while the roller *91* on the other end of the lever *90* will be elevated to the position shown by full lines in Figure 8.

Suitable means is provided for intermittently engaging and depressing the roller *91* of the lever *90* for rocking said lever from its normal position and thereby operating the rod *88* and lever *87* for opening the valve *17* as the several conduits *85* on the carrier are sequentially brought into registration with the discharge nozzle *16* of the melting pot and for this purpose a series of upright levers *93*, one for each work-holder, are respectively pivoted intermediate their ends at *93'* to the upper ends of the brackets *83*, the upper arms of the levers being relatively short and provided with rollers *94* engaging the outer end faces of their respective work-clamping members *77*.

The lower arms of said levers are extended downwardly and provided with adjustable terminal members *94'* which are movable in the horizontal plane as *m'*. Figure 8 of the upper portion of the roller *91* as the carrier is rotated for engaging and depressing said roller and adjacent end of the lever *90* to effect the opening of the valve *17* through the medium of the rod *88* as each conduit *85* on the carrier is brought into registration with the discharge nozzle of the melting pot.

These levers *93* are also movable independently of each other about the axis of their respective pivots *93'* against the action of retracting springs *95* which serve to yieldingly hold the rollers *94* in engagement with the clamping member *77* and also to return their respective levers into engagement with adjustable limiting stops *95'*, see Figures 2 and 3.

As previously stated, during the rotation of the work-holders through the arc Figure 13 designated by the expression "load and unload", the clamping member *77* will be moved to its open or outermost position, thereby rocking the lever *93* to the position shown in Figure 3, thus causing the lower terminal end thereof to travel in an arc some distance to the inside of the roller *91*.

In order to accomplish this opening movement of the clamping member *77* a cam

collar —96— is keyed to the upright post —7— and provided with a radially extending wing —96'— to which is secured a cam segment —97— concentric with the axis of the post and of a circumferential length proportionate to the length of the "loading and unloading" arc shown in Figure 13, the heel of the lower edge of the segment being provided with a relatively short inclined cam face —97'— while the remaining portion of said lower edge is substantially horizontal, see Figures 2, 3, 15, 17 and 18.

The several housings —60— for the clutch and brake members previously described, are provided with a corresponding number of brackets —98—, said brackets being secured to portions of the housings —60— directly under the pulley —56— as shown in Figure 3.

A like number of bell crank levers —99— are pivoted at —99'— to their respective brackets —98— to extend through openings in opposite sides of the housings —60—, the inner arms of said levers being provided with rollers —100— a distance from the axis of the post —7— corresponding to the radial distance of the cam segment —97— and arranged to travel along and against the lower edges of said segments as shown more clearly in Figure 3 so that when the carriage —19— with the levers —99— thereon are rotated about the axis of the post —7— the rollers —100— will be successively brought into engagement with the cam —97'— for sequentially depressing the corresponding arms of the levers —99— and effecting a corresponding upward movement of the outer ends of the levers which are provided with adjustable members —100'—, Figure 3.

Cooperating with the outer ends of the levers —99— are a corresponding number of bell crank levers —101— each of which is pivoted at —101'— to the corresponding housing —60— and is provided with a plurality of, in this instance, three arms —102—, —103—, and —104—, the members —100'— of the levers —99— being arranged to engage the undersides of the arms —102— for transmitting motion therefrom to the levers —101— as the inner ends of the levers —99— are rocked downwardly by the cam segment —97—.

Each arm —103— of the bell crank lever —101— extends upwardly from the corresponding pivot —101'— and is preferably forked and engaged with the inner end face of the plate —76— which, it will be remembered, is connected by the tie rods or bolts —75— to the outer clamping plate —77— so that when the inner end of the lever —99— is depressed by the cam segment —77—, the arm —103— will force the plates —76— and —77— outwardly or to their open positions against the action of the springs —78— to permit the insertion of the work

—a— between the plates —77— and —72— as shown in Figure 3, while the work-holders are passing through the arc designated as "load and unload" in Figure 13.

As soon as each roller —100— passes beyond the end of the cam segment —97—, the corresponding levers —99— and —101— will be released and the clamping member —77— will be automatically closed against the previously inserted work by the springs —78— thereby returning the levers —101— and —99— to their normal positions with the rollers —100— elevated above the horizontal plane of the lower edge of the cam segment —97— ready for a repetition of the opening operation of the clamping member —77—, as previously explained.

This opening and closing movement of the clamping member or boss —77— from and upon the work as thus far explained, is entirely automatic, but in some instances it may be necessary to open any one or more of the clamping members or jaws —77— at will and for this purpose is provided a corresponding number of bell crank levers —105— each of which is secured to a rock shaft —105'— which is journaled in suitable bearings —106— on the housing —60— parallel with the pivot or rock shaft —101'— for the lever —101— as shown more clearly in Figures 2, 3, 9 and 11, the outer ends of the rock shafts —105'— being provided with means for receiving a hand lever —h— by which any one of the shafts may be rocked.

As shown more clearly in Figure 11, one of the arms —103— on the rock shaft —101'— is provided with a downward extension —107— adapted to engage a stop pin —108— which is mounted in a socket in the housing —60— and is yieldingly held against the extension —107— by means of a coil spring —109— to reduce the shock incidental to the opening movement of the corresponding work-clamping members —77—, see Figure 9.

One of the arms as —110— of the bell crank lever —105— is arranged to engage the arm —104— of the corresponding bell crank lever —101— as the shaft —105'— is rocked about its axis in one direction for rocking the arm —103— of the bell crank lever against the inner end face of the plate —76— for opening the clamping plate —77— in substantially the same manner as effected by the corresponding lever —99—.

It therefore follows that as soon as the operation of the hand lever —h— ceases or is released the springs —78— will return the arm —103— to its normal position for closing the clamping members —77—.

The return angular movement of each bell crank lever —105— is limited by a stop pin —111— on the housing —60— in the path of movement of the other arm as —112— of

said bell crank lever —105—, see Figures 3, 9 and 11.

The work-supporting plates —71— and clamping members —72— and —77— are surrounded by suitable guards or housings —B— each of which extends around the periphery of the corresponding face plate —71— and is secured to the upper deck —59— of the rotary carrier —19— to rotate therewith, the outer ends of the housings being open to permit the free insertion and removal of the work by the operator above the upper edge of the clamping plate —77—.

In order to expedite the placing and removal of the work upon and from each work-holder as the latter are passing through the "loading and unloading" arc indicated in Figure 13, it is desirable that the work-supporting studs —71'— assume the same position preferably directly over the axis of the corresponding shaft —58—.

For this latter purpose, the inner ends of the several shafts —58— carrying the face plate —71— are provided with indexing plates or rings —113— keyed or otherwise secured thereto to rotate therewith, each indexing plate being provided with a roller —114— eccentrically pivoted thereto to rotate about an axis parallel with the axis of the shaft —58— as shown more clearly in Figures 2, 3, 15, 18 and 19.

Each indexing disc —113— is provided with a peripheral shoulder —115— facing in the direction of rotation of the carrier as indicated by the arrows —8— in Figures 1, 15 and 18.

A collar —116— is keyed or otherwise secured to the stationary posts —7— directly over but in spaced relation to the collar —96— as shown in Figures 2, 3, 15 and 18, said collar being provided with radially projecting arms —117— and —117'— arranged at an angle to each other as shown more clearly in Figures 15 and 18, the radial length of the arm —117— being somewhat greater than that of the arm —117'—.

A lever —119— is pivoted near one end at —120— to the outer end of the arm —117— and has its other end provided with a hook-shaped shoulder —121— directly over the circular path of movement of the indexing discs —113— for engaging the shoulder —115— upon the several discs —113— as the latter are sequentially presented thereto for a purpose presently described, see Figures 15 and 18.

The cam plate —96'— on the hub —96— is also provided with a radially projecting arm —117''— directly under and in spaced relation to the outer end of the arm —117— and upon these two arms are mounted a pair of indexing blocks —122— in the arc of movement of the rollers —114— of the indexing discs —113— but in vertically spaced relation a distance slightly greater than the di-

ameter of said roller to allow the latter to pass therethrough when properly registered therewith.

These indexing blocks —122— also serve as deflectors adapted to be engaged by the roller —114— in case the roller should not be registered with the intervening space for turning the disc —113—, shaft —58— and work-holding plate —71— about the axis of said shaft and thereby to cause the roller —114— to trail therethrough as shown by dotted lines in Figure 18 rather than to pass head on therethrough as indicated by full lines in the same figure.

That is, when the indexing disc —113— assumes the position indicated by dotted lines in Figure 18 with its roller —114— trailing through the intervening space between the blocks —122—, the work-supporting stud —71'— on the face plate —71— will be in its uppermost central position ready to receive the work as shown by dotted lines in Figure 2.

On the other hand, if any one or other of the discs —113— approaching the space between the blocks —122— should assume a position to bring its roller —114— foremost in registration with said space as shown by full lines in Figure 18, then the shoulder —115— on the periphery of the disc would be brought into engagement with the hook-shaped shoulder —121— on the lever —119— before the roller enters the space between said blocks, thereby causing the disc —113— to rotate in the direction indicated by the arrow α through an angle sufficient to cause the roller to engage the face of the upper block —122— above the axis of the disk so that as the disk continues its planetary motion about the axis of the post —7— the engagement of the roller with the upper block would cause a further angular movement of the disc until brought to the rear of said axis in which position it would be free to trail through the space between the blocks, thereby causing a corresponding angular movement of the shaft —58— and face plate —71— carried thereby to bring the work-supporting stud —71'— to its upper central position ready to receive the work.

If, however, the disc —113— should assume a position with the roller forward of and below the axis of the disc the roller would then engage the lower block —122— thereby causing angular movement of the disc —113— together with the shaft —58— and face plate —71— until the roller is free to trail through the passage between the blocks with the result that the work-supporting pin —71'— will be brought to its uppermost central position ready to receive the work.

The pawl or lever —119— is provided with a relatively short extension —123— adapted to engage an adjustable stop screw —124—

on the arm —117— to limit the downward movement of its disc-engaging end, while the discs are out of registration with the lever.

This indexing of the work-holder takes place during the angular planetary movement of each work-holder through the arc designated by the words "index face plate" in Figure 13, or just preceding the "load and unload" positions of the work-holders.

As previously explained, each clutch and brake member —65— is automatically operated to alternately engage and dis-engage the brake drum —62'— and pulley —56— at certain intervals during each revolution of the carrier —19— and in Figure 13 is shown a chart indicating the planetary circular path of movement of each work-holder and the various operations which take place at different angular positions of the work during each revolution of the carrier.

For this latter purpose, a cam ring —125— is keyed or otherwise secured to the upright post —7— preferably between the collars —96— and —116— and in the horizontal plane of rotation of the several shafts —58— and their respective plungers —80— and —80'—, Figures 2, 3, 16 and 18.

A bracket —126— having a base flange —126'— is secured by bolts —127— or equivalent fastening means to the inner end face of each of the housings —60— to extend inwardly therefrom toward the axis of the post —7— with its base flange preferably extending around the hub of the adjacent indexing disc —113—, said bracket being provided with a transverse opening —128— in which the indexing disc —113— and adjacent end of the plunger section —80'— are rotatable without frictional engagement with any part of the bracket which it will be understood is held against rotation by the bolts —127—, see Figures 3 and 16.

The inner end of the bracket —126— is provided with a central opening —129— coaxial with the axis of the shaft —58— and also radial with reference to the axis of the post —7— for receiving an axially movable spindle —130—.

The inner end of this spindle —130— is provided with a bifurcated head —131— engaging in a radial slot —132— in the adjacent inner end of the bracket —126— to hold the spindle —130— against angular movement about its axis.

A roller —133— is journaled in the inner end of the head —131— and engages the perimeter of the cam ring —125—.

The outer end of the spindle —130— is provided with a threaded socket —134— engaged by an adjusting screw —135— having its outer end abutting against an anti-friction end thrust bearing —136— on the inner end of the plunger section —80'— as shown more clearly in Figure 3.

The inner end of this plunger section

—80'— is provided with shoulders —137— screwed or otherwise secured thereto to form an abutment for the adjacent end of a coil spring —138— which serves to urge the plunger section —80'— and spindle —130— 70 inwardly for yieldingly holding the roller —133— in contact with the perimeter of the cam ring —125—.

The cam ring —125— is provided with two peripheral cam projections —139— and 75 —140— having their peripheral faces concentric with the axis of the ring and of equal radii but of different circumferential lengths, the length of the projection —139— being considerably less than that of the projection 80 —140—, see Figure 16.

The portion —u— of the periphery of the cam-ring —125— between the cams —139— and —140—, and the opposite portion —w— of said periphery are concentric with the axis 85 of the post but of different radii less than that of the cams, the radius of the portion —u— being slightly greater than that of the portion —w— for causing each clutch member —65— to assume and to dwell in a neutral position out of engagement with the corresponding brake drum —62'— and its pulley —56— while the adjacent roller —133— is engaged therewith or during the indexing period 90 represented on the chart Figure 13 as previously explained.

The radial lines passing through the centers of these projections form an angle of approximately 90 degrees more or less each projection acting upon each of the rollers —133— to release the clutch member —65— from engagement with the pulley —56— and to force the same into engagement with the brake drum —62'— for temporarily stopping 105 the rotation of the corresponding shaft —58— immediately preceding and following the indexing operation.

The cam —139— regulates the brief interval of engagement of the clutch member —65— with the brake drum —62'— immediately following the "cooling" period, while the cam —140— serves to hold the clutch —65— in engagement with the brake drum during the period of "unloading and loading" 110 the pieces of work from and upon the work-holder and just preceding the registration of the conduits —85— with the discharge nozzle —16— of the melting pot —13—.

The remaining greater portions —w— of the periphery of the cam ring —125— regulate the cooling period of the molten metal 115 after it has been introduced into the work during which the clutch members —65— are released from engagement with the brake drums —62'— and engaged with their respective pulleys —56— through the medium 120 of the springs —138—, Figure 3.

Operation

In order that these several operations may 130

be clearly understood, I have shown in Figure 13 a chart representing the circular path of movement of the several conduits —85— past the discharge nozzle —16— and also representing the various operations which take place at different positions of each work-holder during one revolution of the carrier —19—.

For example, assuming that the carrier is rotating in the direction indicated by arrow —y— and that the molten metal is to be discharged from the nozzle —16— into the work at the position indicated by the word "pour" in the chart. Then, as each work-holder is carried through the relatively short arc designated by "fixture open", the clamping plate —77— will be opened by means of the cam —97— through the medium of the levers —99— and —101— and connecting rods —75— and will be held in this position during the travel of the work-holder through the arc designated by "load and unload", Figure 13 and corresponding to the circumferential length of the cam —97— Figures 15, 17 and 18.

During this travel of the work-holder through the arc indicated by "load and unload", the operator will remove the piece of work into which the casting has been formed and will replace it with another piece of work upon the supporting stud —71'—.

Immediately upon the travel of each roller —100—, of the corresponding lever —99— from the end of the cam —97—, the clamping member —77— will be closed against the work by means of the springs —78— for holding the work in operative position during the succeeding casting operation.

It will be noted, however, that immediately following the initial opening of the clamping member —77— by cam —97— as indicated at the position "fixture open", the roller —132— will ride upon the cam —140— thereby forcing the clutch member —65— into engagement with the brake drum —62— for temporarily stopping the rotation of the corresponding shaft —58— and its work-holder —70— during the movement of the work-holder through the arc designated by "brake", or while the work is being removed from and replaced upon said work-holder.

When the roller —132— leaves the end of the cam —140— the spring —138— acting through the plunger sections —80'— and —80— will withdraw the clutch —65— from engagement with the brake drum —62— and force it into frictional engagement with the rotating pulley —56— thereby causing the work-holder with the work thereon to rotate at its highest speed during the travel of the work-holder through the arc indicated by the words "up to speed," at which time it will be remembered that the work is firmly clamped to the work-holder by the closing

of the clamping member —77— as previously explained.

By the time the rotation of the work-holder with the work thereon reaches its highest speed of rotation, the conduit —85— on the carrier will have been moved about the axis of the carrier directly beneath the discharge nozzle —16— of the melting pot while travelling through the relatively short arc indicated by the word "pour" for receiving the molten metal and discharging the same into the registering bearings —b— of the work —a—.

As soon as the clamping plate —77— is forced to its closed position upon the work, the upper end of the lever —93— will follow and cause its lower end —94'— to be moved outwardly by the spring —95— a distance from the axis of the carrier equal to the distance of the roller —91— from the same axis so that while the conduit —85— is registered with the nozzle —16— the member —94'— will engage the upper face of the roller —91— and depress the adjacent end of the lever —90— thereby causing the opposite end of said lever to raise the rod —88— for opening the valve —17—.

As soon as the member —94'— is carried past the roller —91— by the continued rotation of the carrier —19—, the lever —90— and rod —88— will be released thereby allowing the weight of the rod, aided by the weight of the valve, to close the latter, this opening and closing of the valve taking place only while the conduit —85— is passing across the underside of the discharge nozzle —16— designated by the word "pour" in the chart, Figure 13, corresponding to the relative position of the roller —91—.

The stop screw —95'— is preferably adjusted to leave a sufficient clearance between it and the lever —93— to allow the roller —94— to press the jaw —77— firmly against the work —a— at which time the lower end —94'— of said lever will be in position to engage and depress the roller-end of the lever —90— for temporarily opening the valve —17—.

In the event, however, that the operator should fail to place a piece of work in the work-holder while the latter is passing through the arc designated by the indicia "load and unload," Figure 13, it is evident that during that period the clamping jaw —77— would continue to move inwardly toward its companion member —72— which would allow the upper end of the lever —95'— to follow the jaw and thereby to cause the lower end —94'— of said lever to be moved outwardly a sufficient distance to prevent its engagement with the roller —91—, thus preventing the opening of the valve —17— through the medium of its operating rod —88—, it being understood that the clearance between the stop screw —95'— and lever would be sufficient for that purpose,

but would prevent the outward swinging movement of the levers into engagement with any fixed part of the frame section as —3— or other parts mounted thereon.

It will also be evident that in case the jaw —77— should remain open while passing through the "load and unload" arc, the lower end —94'— of the lever —93— would travel at the inside of the roller —91— thereby avoiding contact therewith and allowing the valve to remain closed to prevent discharge of the molten metal from the nozzle —16— during that period.

It will be remembered that during this pouring operation through the relatively short arc indicated by the indicia "pour", Figure 13, the work-holder carrying the work into which the molten metal has been discharged will be rotating under its maximum speed due to the engagement of the corresponding roller —132— with the peripheral portion —w— of the cam ring —125— which causes the clutch member —65— to engage the continuously rotating pulley —56— and that this maximum speed rotation of the work-holder with the work therein will continue through the entire length of the peripheral portion —w— of the cam or through the corresponding arc designated by the indicia "cooling", Figure 13, thereby causing the cylindrical formation and cooling of the molten metal in the bearing —b— of the work —a—.

Immediately following this casting operation the roller —132— will engage the cam —139— of the ring —125— to temporarily shift the clutch member —65— out of engagement with the pulley —56— and into engagement with the brake drum —62— for stopping the rotation of the work-holder during the travel of the latter through the arcs indicated by the indicia "brake on" and "brake".

As soon, however, as the roller —132— leaves the end of the cam —139— indicated by the indicia "brake off" Figure 13, said roller will be forced into engagement with the peripheral portion —u— of the cam ring —125—, thereby causing the clutch member —65— to be withdrawn from engagement with the pulley —56— to a neutral position between said pulley and brake drum —62— or out of engagement with both the pulley and the brake drum, thereby stopping the positive driving of the work-holder and allowing said work-holder to be adjusted rotarily by means of the indexing mechanism in the manner previously described, thus permitting the work-supporting stud —71'— on the face plate —71— to be brought to its uppermost position while traveling through the arc designated by the indicia "index face plate" Figure 13, which corresponds to the length of the peripheral portion —u— of the cam ring —125—.

It will be noted, however, that the cam —97'— of the cam plate —97—, Figures 15, 17 and 18, is arranged to be engaged by the roller —100— just at the end of the indexing operation for operating the corresponding levers —99— and —101— to open the jaw —77— as designated by the indicia "fixture open", Figure 13.

At about the same time or immediately following this opening of the fixture, the roller —132— will be brought into engagement with the cam —140— for shifting the clutch member —65— from its neutral position into engagement with the brake drum —62— thereby stopping the rotation of the work-holder about its axis preparatory to removing the work with the casting therein and replacement with a new piece of work, thus completing the several operations upon the work in one of the work-holders during one revolution of the work-holder, it being understood that these operations will be repeated upon each piece of work as it is placed in each work-holder as the latter are successively presented to the positions designated by the indicia "load and unload" in the chart, Figure 13.

It will be noted that aside from placing each piece of work upon each work-holder as the latter are presented to the "load and unload" positions and the removal of the completed work at the same position, the remaining operations are entirely automatic and practically continuous for the reason that the rotation of the carrier —19— about its axis and that the rotation of the pulleys —56— about their respective axes are continuous.

Under these conditions, it is obvious that a machine of the character shown and described will be capable of turning out a large amount of work within a relatively short period of time by reason of the fact that a multiplicity of, in this instance, six pieces of work will be finished during each revolution of the carrier, but it is evident that some changes may be made in the detail construction of the carrier, but it is evident that some the spirit of this invention.

What I claim is:

1. In a centrifugal gang-casting machine, a rotary carrier, means for rotating the carrier, a plurality of work-holders mounted on the carrier to move therewith about its axis of rotation, means for introducing molten metal into the work of each work-holder as the latter are successively brought to a predetermined position, and means for rotating each work-holder when the molten metal is introduced into its work, the means for introducing molten metal into the work including a plurality of valve-operating members, one for each work-holder mounted on the carrier, and means actuated by each of said members as the work-holders are successively

brought to said predetermined position for opening the valve.

2. In a centrifugal gang-casting machine, a rotary carrier, means for rotating the carrier, a plurality of work-holders mounted on the carrier to move therewith about its axis of rotation, means for introducing molten metal into the work of each work-holder as the latter are successively brought to a predetermined position, and means for rotating each work-holder when the molten metal is introduced into its work, each work-holder including a clamping member movable into and out of engagement with the work in combination with a normally closed self-closing valve controlling the introduction of molten metal into the work, a plurality of valve operating members, one for each work-holder mounted on the carrier and controlled by their respective clamping members to cause them to move to and from their valve operating positions as the corresponding clamping members are closed and opened, and means for successively closing the clamping members upon the work as the work-holders are successively brought to said predetermined position to cause the corresponding valve operating members to be moved to their valve operating positions, and means actuated by said valve operating members when moved to their operative positions for opening said valve.

3. In a centrifugal gang-casting machine, a rotary carrier, means for rotating the carrier, a plurality of work-holders mounted on the carrier to move therewith about its axis of rotation, means for introducing molten metal into the work of each work-holder as the latter are successively brought to a predetermined position, and means for rotating each work-holder when the molten metal is introduced into its work, each work-holder including a clamping member movable into and out of engagement with the work, means controlled by the rotation of the carrier for successively closing said clamping members upon the work as the work-holders are brought to said predetermined position, in combination with a normally closed self-closing valve controlling the introduction of the molten metal into the work, and means brought into action by the closing of each clamping member upon the work for opening said valve.

4. In a centrifugal gang-casting machine, a source of supply for molten metal having a discharge opening, a rotary carrier, means for rotating the carrier, a plurality of work-holders mounted on the carrier about its axis of rotation and successively brought into position for receiving molten metal from said opening, a normally closed self-closing valve controlling said opening, means actuated by the carrier for opening said valve as each work-holder is brought into alinement with

the discharge opening to allow the molten metal to flow into the work of the corresponding work-holder, and means for rotating the work-holders as they are successively registered with said discharge opening.

5. In a centrifugal gang-casting machine, a source of supply for the molten metal having a discharge nozzle, a rotary carrier, means for rotating the carrier, a plurality of work-holders mounted on the carrier about its axis of rotation and movable therewith to successively align its work-holders with said nozzle, means for rotating the work-holders as they are successively aligned with the nozzle, each work-holder including a movable clamping member, means for closing the clamping members upon the work as the work-holders are brought into alinement with the nozzle, a valve controlling the discharge of the molten metal through said nozzle, and means actuated by the rotation of the carrier about its axis for opening said valve as the work-holders are successively aligned with the nozzle to allow the molten metal to flow into the work of the corresponding holder.

6. In a centrifugal gang-casting machine, a source of supply for the molten metal having a discharge nozzle, a valve controlling the discharge of the metal through said nozzle, a rotary carrier, means for rotating the carrier, a plurality of work-holders mounted on the carrier and successively movable therewith into alinement with the nozzle to permit its work to receive molten metal from said nozzle, each work-holder having a clamping member movable into and out of engagement with the work, means for rotating the work-holders as they are successively brought into alinement with the nozzle, valve operating members one for each work-holder mounted on the carrier and movable with their respective clamping members, an additional valve operating member normally in the path of movement of the first named valve operating members when the clamping members are closed upon the work and adapted to be operated by said first named valve operating members as the work-holders are successively aligned with the nozzle for opening said valve.

7. In a centrifugal gang-casting machine, a source of supply for the molten metal having a discharge nozzle, a valve controlling the discharge of the metal through said nozzle, a rotary carrier, means for rotating the carrier, a plurality of work-holders mounted on the carrier and successively movable therewith into alinement with the nozzle to permit its work to receive the molten metal from said nozzle, each work-holder having a clamping member movable into and out of engagement with the work, means for rotating the work-holders as they are successively brought into alinement with the nozzle, valve operating members one for each work-holder mounted on the carrier and movable with

- their respective clamping members, an additional valve operating member normally in the path of movement of the first named valve operating members when the clamping members 5 are closed upon the work and adapted to be operated by said first named valve operating members as the work-holders are successively alined with the nozzle for opening said valve, said first named valve operating members 10 being moved to a position for preventing engagement with the second valve operating member when the corresponding clamping members are not engaged with the work.
8. In a centrifugal gang-casting machine, 15 a rotary carrier, means for rotating the carrier, a plurality of work-holders mounted on the carrier about its axis to move therewith, means for introducing molten metal into the work of each work-holder as the work-holders 20 are successively brought to a predetermined position, separate driving devices for rotating the several work-holders, one for each work-holder and each device including a continuously 25 rotating member and a clutch member movable into and out of engagement therewith, and means brought into action by the rotation of the carrier through different parts of each revolution for moving the clutch member into and out of engagement with its continuously 30 rotating member.
9. In a centrifugal gang-casting machine, a rotary carrier, means for rotating the carrier, a plurality of work-holders rotatively mounted upon the carrier to move therewith, means for introducing molten metal into the work of each carrier as they are successively brought to a predetermined position, each work-holder including a clamping member movable into and out of engagement 35 with the work, means for closing the clamping member upon the work as the work-holders are successively brought to said predetermined position, said means including a relatively stationary cam, and means mounted 40 on the carrier to move therewith for transmitting motion from the cam to said clamping member.
10. In a centrifugal gang-casting machine, 45 a rotary carrier, means for rotating the carrier, a plurality of work-holders mounted upon the carrier about its axis of rotation, means for introducing molten metal into the work of each work-holder as the latter are successively brought to a pre-determined position, separate driving devices for the several work-holders each including a continuously 50 rotating member and a clutch member in combination with means including a relatively stationary cam for engaging the clutch with said continuously rotating member while the molten metal is introduced into the work of the corresponding work-holder and for disengaging said clutch member during 55 the rotation of the carrier through another part of its revolution.
11. In a centrifugal gang-casting machine, a rotary carrier, a plurality of work-holders rotatively mounted on the carrier about its axis of rotation, means for intermittently rotating the work-holders during each revolution of the carrier, means for indexing each work-holder about its axis during each revolution of said carrier and during the non-rotating period of said work-holder, for properly positioning the work-holders to receive the work, and means for introducing molten metal into the work of each work-holder as the work-holders are successively brought to a predetermined position.
- In witness whereof I have hereunto set my hand this 13th day of October, 1931.
- LLOYD W. MOULTON.
